UNITED STATES PATENT OFFICE.

BENJAMIN E. GETCHELL, OF GREENSBURG, PENNSYLVANIA, ASSIGNOR TO RAILWAY AND INDUSTRIAL ENGINEERING COMPANY, OF GREENSBURG, PENNSYLVANIA, A CORPORATION OF PENNSYLVANIA.

CURRENT-LIMITING DEVICE.

1,427,203.

Specification of Letters Patent. Patented Aug. 29, 1922.

Application filed August 25, 1917. Serial No. 188,256.

To all whom it may concern:

Be it known that I, BENJAMIN E. GETCHELL, a citizen of the United States, residing at Greensburg, in the county of Westmoreland and State of Pennsylvania, have invented certain new and useful Improvements in Current-Limiting Devices, of which the following is a specification.

This invention relates to controlling devices for electric circuits, and more particularly to devices for limiting the amount of current supplied to consumers in systems where meters are not employed.

In such systems it is the common practice to serve customers on what is known as a flat rate basis, the contract permitting the consumer to use any amount of current he desires up to a certain maximum, in consideration of fixed monthly or yearly payments. Obviously, it is necessary to protect the service company by providing means for preventing a consumer from using more current than his contract calls for.

Various devices have heretofore been proposed for accomplishing this purpose, many of them being electromagnetically operated and usually serving to cause a rapid flickering of the lights in case an attempt is made to use too much current. These prior devices have been found more or less defective in practice, owing to rapid deterioration of the contacts, or to other causes. With some of them it has been found possible to operate heating apparatus even though consuming an excessive amount of current, since the making and breaking of the current occurs with such rapidity as to maintain such apparatus at least in partially operative condition.

The object of the present invention is therefore to provide an improved device of this character in which the interruptions of the circuit take place much more slowly, and in which the ratio between the "on" and "off" periods can be adjusted as desired. It is obvious that by making the "off" period relatively large, it will be impossible to maintain the temperature of heating apparatus when the predetermined load is exceeded. A further object is to provide a device in which the circuit is made but never broken at the controlling contacts, thereby preventing deterioration of such contacts due to sparking. To this end, the invention

contemplates the use of a hot wire or thermal element for closing the controlling circuits, such circuits containing electromagnetic means for opening and closing the main circuit.

The principles involved in the invention admit of application to many varying conditions and may be embodied in a number of different forms, some of which are illustrated in the accompanying drawings, forming a part of this specification.

In these drawings,

Fig. 1 is a diagrammatic view illustrating my improved controlling device in its simplest form, as applied to an ordinary two-wire circuit;

Fig. 2 is a similar view illustrating the connections which may be employed on an alternating circuit, where it is desired to dim the lights instead of extinguishing them;

Fig. 3 is a view similar to Fig. 1, but showing a slightly different method of connecting the electromagnetic controlling means;

Fig. 4 is a view similar to Fig. 3, except that the device is arranged for dimming the lights instead of extinguishing them;

Fig. 5 is a view similar to Fig. 4, showing another method of dimming;

Fig. 6 is similar to Fig. 1, except that it is applicable only to alternating current circuits, a transformer being employed;

Fig. 7 shows a similar arrangement, except that the controlling current is obtained from a secondary winding on the electromagnetic means itself instead of a separate transformer;

Fig. 8 is a view showing the application of my improved controlling device to a three-wire circuit employing alternating currents; and,

Fig. 9 is a view similar to Fig. 8, but showing the controlling device applied to a two-phase alternating current circuit.

Referring to the drawings in detail, and particularly to Fig. 1, the incoming line wires are designated by 1 and 2. These are connected to the binding posts 3—4 of the controlling device, while other binding posts 5—6 thereof receive the mains 8—9, to which the load 10 is connected. The wires 2 and 9 are, in fact, continuous, since the binding posts 4 and 5 are joined by a cross connection 7.

The essential part of my improved control-

ling device is a thermal element or hot wire 15, held at its ends in fixed binding posts 13 and 14. This hot wire is connected at its middle 16, by means of a conducting link 17, 8 with a resilient contact finger or switch member 18. This contact finger preferably consists of a spring trip having at one end a spiral 19, secured at its center to a fixed support 19'. The free end of the spring 18 10 plays between adjustable contact points 20 and 21, as will be hereinafter more fully described.

In addition to the thermal element 15, I provide an electromagnetic switch actuating 15 device which is here represented as comprising a pair of solenoid coils 23 and 26, in which works a common core 32.

The thermal element 15 is connected in series with the load, the current passing in 20 from binding post 3, over wire 28, to binding post 13, thence through the wire 15 to binding post 14, whence it passes through conductor 8', binding post 6, wire 8, to load. In the conductor 28 is interposed a pair of 25 spaced contacts 29, adapted to be bridged by a switch member 30, carried by a rod 31, secured to the core 32 of the solenoid.

The contact 20 is connected by a wire 22 with one end of the coil 23, the other end of 30 which is connected by wire 24 to one side of the line at binding post 5. The contact 21 is connected by wire 25 with one end of the coil 26, the other end of which is connected by wire 27 to the other side of the line at 35 binding post 3.

The operation of the device shown in Fig. 1 is as follows: Upon the occurrence of an overload on the mains 8—9, the wire 15 is excessively heated and caused to expand. 40 This permits the contact finger 18 to move under the influence of the spring 19 until it engages contact 20. Thereupon a circuit is closed through the solenoid 23 as follows: From line 1, through wire 28, hot wire 15, 45 conducting link 17, contact finger 18, contact 20, wire 22, solenoid 23, wire 24 to the other side 2 of the line. This energizes solenoid 23 which draws the core 32 to the right, thus breaking the main circuit at switch 50 contacts 29. It will be noted that the opening of these contacts also interrupts the circuit just traced through solenoid 23 so that this solenoid cuts itself out when it operates.

Immediately after the circuit is opened 55 the wire 15 begins to cool and contract, drawing the contact finger 18 over towards contact 21. After a definite time interval, such contraction causes 18 to engage 21 and thereupon a circuit is closed through solenoid 26 60 as follows: From line 1 to binding post 3, wire 27, solenoid 26, wire 25, contact 21, contact finger 18, conducting line 17, hot wire 15, binding post 14, conductors 8' and 8, through the load 10 to conductor 9, and 65 thence back to the other side of the line.

This energizes solenoid 26 and causes the core 32 and switch 30 to be restored to the position shown in the drawings, thus again closing the main line circuit. It will be seen therefore that the solenoids 23 and 26 are 70 energized only momentarily and that the operation of each serves to deprive itself of current. It will also be observed that the circuit is only made at the contacts 20 and 21, and is never broken at these contacts while any current is flowing. Therefore, these contacts are not subjected to destructive sparking and consequent deterioration.

By making contacts 20 and 21 adjustable, 80 it is possible to secure any desired relation between the time that the switch 29 remains open and the time that it is closed. By adjusting the contact 20 the definite load at which the circuit will open can be determined. By adjusting the contact point 21 the duration of the period of cut-off is determined. This period may, of course, be lengthened by covering the hot wire 15 with a protective coating of asbestos or the like, 90 which tends to retard heat radiation.

It will be obvious that the greater the overload the shorter will be the period during which the circuit remains closed, since a shorter time will be required to heat the 95 thermal element. The time that the circuit remains open, however, is substantially always the same and is governed by the predetermined setting of the contact.

This thermally controlled interruptor or 100 current limiting device will, it is seen, operate at a comparatively low rate of speed. That is to say, instead of rapid vibrations of 200 to 500 per minute, as occurs with many prior devices, my improved apparatus will 105 ordinarily operate at from 2 to 15 times per minute. By properly adjusting the contacts 20 and 21, the "off" period may be made many times greater than the "on" period. By way of illustration, we will suppose that 110 the consumer's contract calls for a maximum of 100 watts and that the contacts are set for an "off" period of 15 seconds. Now, if an attempt is made to connect a 500 watt heating device on the circuit it will require only 115 about $\frac{1}{5}$ of a second to heat the thermal element 15 up to the point required for breaking the circuit. It will thus be seen that with an "on" period of $\frac{1}{5}$ of a second and an "off" period of 15 seconds, there is no 120 possibility of maintaining the temperature of such a heating device high enough to be of service.

Referring to Fig. 2, it will be seen that instead of connecting the thermal element 15 125 directly in series with the load, as in Fig. 1, it is connected to the secondary winding 34 of a series transformer. This transformer has a primary winding 33, through which the load current passes. The ends of the 130

secondary winding 34 are connected by wires 11 and 12 with binding posts 3 and 6, and the wire 11 is also connected with the line wire 1 by means of the cross connection 37. 5 From binding post 3 extends a wire 38 to binding post 13, supporting the thermal element, a pair of switch contacts 39 being interposed in such wire and normally closed by means of the switch 30. The wire 24 10 which extends from one end of the solenoid 23 to binding post 5 and thence to line 2, has connected therein a pair of spaced contacts 36, adapted to be bridged by a second switch member actuated by the core 32 simultaneously with the switch member 30.

20 The windings 33 and 34 constitute an impedance. This is relatively low when the terminals of coil 34 are short circuited through the thermal element 15, as shown in the drawings, and relatively high when the circuit of coil 34 is open.

The operation of this arrangement is as follows: Upon the occurrence of excess load, the wire 15, receiving current from the 25 secondary coil 34, is heated and expands until the switch finger 18 engages contact 20. This closes a circuit from line 1 through connection 37, wire 11, binding post 3, wire 38, thermal element 15, conducting link 17, 30 switch finger 18, contact 20, wire 22, coil 23, wire 24, switch 35—36, binding post 5 to line 2. This energizes solenoid 23 which pulls the core 32 to the right, thus moving switches 30 and 35 out of engagement with 35 their respective contacts. Switch 30 opens the circuit of coil 34, thus increasing the impedance of the main line and dimming the lights 10. At the same time switch 35 opens the circuit of solenoid 23 and stops the flow 40 of current therethrough. When the wire 15 cools sufficiently, switch finger 18 will be drawn over against contact 21 and thus closes a circuit as follows: Beginning at one side of secondary coil 34, current flows 45 over wires 11 and 27 to coil 26, thence through wire 25 to contact 21, spring finger 18, connecting link 17, thermal element 15, to binding post 14, thence over wires 38' and 12 back to the other side of secondary 50 coil 34. This energizes coil 26 which restores the core and associated parts to the position shown in the drawing, thus short circuiting the terminals of coil 26 and also the terminals of coil 34, thereby reducing 55 the impedance of the main line and permitting the lights to burn at full candle power until the thermal element acts again.

It will be seen that the arrangement just described serves to cause a periodic dimming 60 of the lights instead of extinguishing them altogether, and it will of course be understood that this particular arrangement is applicable only to an alternating current circuit.

65 Referring now to Fig. 3, it will be seen

that this arrangement is quite similar to Fig. 1 except that auxiliary contacts for controlling the solenoid windings are employed. As in Fig. 1, the thermal element 15 is in series with the load through wire 1, binding 70 post 6, wire 28', binding post 14, binding post 13, wire 38, and wire 8. When the load becomes excessive and contact finger 18 engages contact 20, the solenoid 23 is energized, as in Fig. 2, through a circuit including the switch 35—36. However, in this arrangement the wire 27 extending from the coil 26 to line, as in Fig. 1, has included therein a pair of spaced contacts 40 which are also governed by the switch 35. When, 75 therefore, the core 32 moves to the right under the influence of coil 23, the switch 35 breaks the circuit of coil 23 at contacts 36 and establishes the circuit of coil 26 through contacts 40. Hence, when upon the cooling 80 of the thermal element 15 the contact finger 18 engages contact 21, the coil 26 is connected directly across the line, the same as coil 23. This modification is designed for the purpose of increasing the strength of the 85 closing solenoid, which is particularly desirable on low capacity installations.

In Figs. 4 and 5, I have shown other arrangements for dimming which are equally applicable to both direct and alternating 90 current circuits. In these figures, the same auxiliary contacts 36 and 40, controlled by the switch 35, are employed for governing the circuits of the solenoid coils 23 and 26, and the thermal element 15 is in series with 95 the load, as in Fig. 3.

However, in Fig. 4, instead of interrupting the main circuit when the contacts 39 are opened, as in Fig. 3, I provide means for inserting a resistance in series with the load. 100 This resistance in Fig. 4 is shown at 41 as connected between the wires 38 and 28' in parallel with the hot wire 15. The resistance 41 is, however, normally short circuited by such hot wire, and when this short circuit is removed by the opening of switch 39, the load current necessarily passes through resistance 41, on its way to main 8, connected with the load.

In Fig. 5, the resistance 42 is connected in 115 shunt across the terminals of switch 39 instead of being connected like resistance 41 in the preceding figure. When the switch 39 opens, therefore, the resistance 42 is thrown in series with the hot wire 15 and 120 the load, and thus reduces the current through such wire sufficiently to allow it to cool and actuate the closing solenoid after a given period. It will be seen that by making the resistance 42 adjustable and giving 125 it the proper value, the device may be set so that sufficient current will flow through 42 and wire 15 to maintain the latter at a temperature so high as to prevent the contact finger 18 from engaging the restoring con- 130

tact 21 at all, so long as the excess load is connected to the mains. Any lights on the circuit will, of course, remain constantly dim through such a period also.

5 Figs. 6, 7, 8, and 9 relate to arrangements adapted for alternating circuits.

Fig. 6 is identical with Fig. 1 except that the thermal element 15, instead of being connected in series with the load, is connected 10 by wires 48 and 49 with the secondary 46 of a series transformer. This transformer has its primary winding 44 connected directly in series with the load through wires 28, 45, and 43, so that, as is well understood, the 15 current in the circuit including the secondary winding 46 is always proportional to the load. The cross connection 47 between the primary and secondary circuits is provided in order to properly energize the solenoids 20 23 and 26, the function of this cross connection being identical with that of cross connection 37, explained in the description of Fig. 2.

This arrangement of using a series transformer permits the adoption of a uniform 25 thermal element of standard size for all capacities, the transformer windings being simply proportioned to suit various conditions. Moreover, the use of a transformer 30 of this kind eliminates all danger of damage to the thermal element by short circuits.

In Fig. 7, I have shown how the thermal element can be operated by means of a 35 secondary winding placed on the operating solenoid itself. This winding is indicated at 57 and is shown as associated with the winding 23 of the opening solenoid. Instead of the contact 20, I provide an auxiliary spring finger 52, secured to a fixed 40 support 53, and normally in engagement with a contact 54, connected to the thermal element 15 by means of a wire 55. The secondary winding 57 has one end connected by means of a wire 58 with the opposite 45 end of the thermal element 15, and its other end connected by means of a wire 56 with the contact 54. It will be apparent that the opening solenoid 23 is in series with the load through wires 24' 50 and 8'. When the current becomes excessive, a correspondingly increased current is generated in the secondary circuit, including the thermal element 15 and coil 57, thus permitting the element 15 to expand and 55 the contact finger 18 to engage the finger 52 and cause it to break connection with contact 54, (the spring 19 of finger 18 being stronger than the spring of 52). The disengaging of finger 52 and contact 54 opens 60 the circuit of secondary winding 57, which has heretofore served to counteract the winding 23, and permits the solenoid 23 to act and open the switch 36. The separation of contacts 52 and 54 also opens the 65 hot wire circuit and permits the wire to

cool, thus causing contact finger 18 to engage contact 21 and energize solenoid 26. The circuit of the latter is as follows:

Beginning at line 1, through wire 27, solenoid 26, wire 25, contact 21, contact finger 18, conducting link 17, thermal element 15, binding post 14, wire 55, joint 53, contact finger 52, wire 56, cross connection 59, to main 8, thence through the load back to main 9 and line 2.

75

Fig. 8 shows my improved controlling device as applied to a three-wire alternating current circuit. The three wires are indicated at 1, 2, and 60, the line 60 running straight through to the load. The solenoid core 32 operates a switch 30 controlling line 1, as in Fig. 1, and also a switch 63 controlling contacts 62, connected with line 2. The secondary winding 46 and co-operating parts are identical in every respect 80 with the corresponding parts shown in Fig. 6. In Fig. 8, however, this secondary winding 46 is associated with two primaries 44 and 61. The winding 44 is connected between the line 1 and main 8 by wires 45 and 43, as in Fig. 6, while the primary winding 61 is connected by wires 7 and 7' to binding posts 4 and 5 to which line 2 and main 9 are attached. In other words, the switch 62—63 and the winding 61 are interposed in the cross connection 7, which appears in Fig. 6. As a result of the arrangement shown, the current in the hot wire circuit including secondary 46, is proportional to the sum of the currents in the 90 outside legs 1 and 2 of the three-wire circuit. No further description of this arrangement seems necessary as it operates in every respect similar to those heretofore 95 described, the only difference being the 100 joint control of both legs of the circuit.

105 It will of course, be obvious that this three-wire arrangement may be modified to produce a dimming action in the same manner as shown in Figs. 2, 4, and 5, or the 110 secondary winding may be associated with the actuating solenoids as in Fig. 7.

Referring finally to Fig. 9, I have illustrated the application of my controlling device to a two-phase alternating circuit. 115 One phase is represented by the wires 1 and 64, and the other phase by the wires 2 and 65. The lines 64 and 65 run straight through to the load, while the lines 1 and 2 contain the switching devices 29—30 and 62—63, 120 similar to those shown in Fig. 8. The solenoid coils 23 and 26 are controlled by the switch member 35, working between the two sets of contacts 36 and 40, as in Figs. 6 and 8. The hot wire 15 is connected in a 125 permanently closed circuit, including the secondary windings 46 and 66, of two transformers, the primary windings 61 and 44 of which are connected with the lines 1 and 2, as in Fig. 8. One end of each of 130

the secondary windings 46 and 66 is connected by means of a common wire 67 with the contact finger 18, while the opposite ends of the windings 46 and 66 are connected by wires 48 and 49 to binding posts 13 and 14, respectively. The current generated in secondary winding 46 flows from such winding over wire 49, half of hot wire 15, connecting link 17, thence through contact finger 18 and common return wire 67, back to 46. The current generated in secondary winding 66 flows from such winding through wire 48, binding post 13, the other half of hot wire 15, conducting link 17, and thence over contact finger 18 and common return wire 67, back to 66. Thus, each half of the thermal wire 15 is heated separately by one of the transformers, but the total expansion of this wire being equal to the sum of the expansions of its two halves, is proportional to the sum of the currents flowing in the two circuits and is therefore proportional to the sum of the currents in the two phases of the polyphase circuit. The solenoids 23 and 26 are operatively connected in shunt across the lines by means of the wire 24, binding post 68, and wires 69 and 70, as will be obvious.

A similar arrangement of transformers and secondary circuits can, of course, be used in connection with a three-phase circuit.

It will also be understood that the arrangement shown in Fig. 9 may be modified to produce dimming, as in Figs. 2, 4, or 5, instead of interrupting the circuit as described.

In conclusion, it may be pointed out that in every modification shown the solenoids which are controlled by the thermal element take current only momentarily and therefore are not subject to heating or other troubles. It will also be noted that in every case the contact finger operated by the thermal element is never required to break its circuit while current is flowing.

It is thought that without further discussion the adaptability and many advantages of my invention will be readily appreciated

by those skilled in the art, and it will suffice to define the novel features in the appended claims.

It is to be observed that in some illustrations the circuit is entirely open, in other the normal condition of the circuit is disturbed in other ways as by the introduction of current reducing means. In the claims I propose to use the expression "interrupting the circuit" to denote any of such changes in the circuit as would disturb the normal working condition.

I claim:

1. In a current-limiting device, the combination with a main circuit, of a thermal element responsive to current flowing in said circuit, said element consisting of a "hot wire" fixed at its ends, a switch member to which the middle of the hot wire is mechanically and electrically connected, a pair of contacts arranged to be engaged by said switch member, means in the main circuit including a switch for increasing the resistance of the circuit and auxiliary circuits connected with said contacts and including each said switch member and a portion of said hot wire, one of said auxiliary circuits including means for opening the said main circuit switch and the other auxiliary circuit including means for closing the said main circuit switch.

2. In a current limiting device, the combination with a main circuit, of a thermal element responsive to current flowing in said circuit, said element consisting of a "hot wire" fixed at its ends, a switch member to which the middle of said hot wire is mechanically and electrically connected, a pair of contacts arranged to be engaged by said switch member, a switch in the main circuit and auxiliary circuits connected with said contacts and including each said switch member and a portion of said hot wire, one of said auxiliary circuits including means for opening the said main circuit switch and the other auxiliary circuit including means for closing the main circuit switch.

In testimony whereof I affix my signature.

BENJAMIN E. GETCHIELL.
